UNITED STATES PATENT OFFICE.

CAROLINE E. ANDERSON, OF PARK CITY, UTAH.

MATERNITY-CORSET.

1,352,422.

Specification of Letters Patent. Patented Sept. 14, 1920.

Application filed August 15, 1917. Serial No. 186,359.

To all whom it may concern:

Be it known that I, CAROLINE E. ANDERSON, a citizen of the United States, residing at Park City, in the county of Summit and 5 State of Utah, have invented certain new and useful Improvements in Maternity-Corsets; and I do hereby declare the following to be a full, clear, and exact description of the invention, such as will enable others 10 skilled in the art to which it appertains to make and use the same.

The invention relates to a maternity corset.

The object of the present invention is to 15 improve the construction of corsets and to provide a simple, practical and efficient maternity corset equipped with a yieldable highly elastic front and provided at the sides and back with means for adjusting the 20 size of the corset so that the corset may be increased in size from time to time as required, whereby the corset will be perfectly adapted for wear during maternity and will be comfortable to the wearer.

25 With these and other objects in view, the invention consists in the construction and novel combination of parts hereinafter fully described, illustrated in the accompanying drawings and pointed out in the claim here- 30 to appended; it being understood that various changes in the form, proportion, size and minor details of construction, within the scope of the claim, may be resorted to without departing from the spirit or sacri- 35 ficing any of the advantages of the invention.

In the drawings:

Figure 1 is a perspective view of a corset constructed in accordance with this invention and shown closed.

Fig. 2 is an elevation of the corset showing the same open or spread to illustrate the construction more clearly.

Fig. 3 is a vertical sectional view through 45 the front portion of the corset, illustrating the overlapped relation of the horizontal elastic strips.

Fig. 4 is a horizontal sectional view on an enlarged scale through the front fastening 50 means.

Fig. 5 is a similar view through one of the side adjusting means.

Fig. 6 is a detail view of the side adjusting means.

Like numerals of reference designate corresponding parts in the several figures of the drawings. 55

In the accompanying drawings, in which is illustrated the preferred embodiment of the invention, the corset shown is divided at 60 the back and at the left hand side of the wearer to form two sections 1 and 2 of unequal size, the section 1 being equipped with the front of the corset and the other section extending from one side of the front to the 65 center of the back, as clearly illustrated in Fig. 1 of the drawings. The front, which is yieldable is composed of a vertical series of horizontally arranged relatively broad overlapped strips 3 of elastic webbing or 70 other suitable material which gradually increase in length from the lowermost strip and which are designed to extend practically entirely across the front of the corset. The upper edge of the lowermost strip is arranged in rear of the lower edge of the next adjacent strip. This arrangement is carried out throughout the entire series of strips. The strips are attached only at the ends to the adjacent portions of the corset and are 75 open or unattached at their upper and lower horizontal edges between the portions 4 and 5, which are reinforced in any desired manner to provide the necessary strength at the attaching means of the elastic. The length 80 of the elastic strips may of course be varied.

The adjacent edges of the sections 1 and 2 at the front of the corset are secured together detachably by suitable fastening 90 means preferably consisting of buttons 6, carried by the section 2 and engaging button holes 7 formed in the section 1. The buttons 6 are preferably mounted on tape 8 but they may be attached in any other desired manner and the front edge of the section 2 of the corset is arranged to form a fly 9 to underlie the button holes. The section 2 is also preferably provided with a bone or stiffener 10 at the inner portion of 95 100 the fly 9 and at the point where the buttons are attached.

The sections 1 and 2 are provided at their sides with adjusting means for varying the size of the corset and the said adjusting 105 means comprises spaced strips 11 extending from the top to the bottom of the corset and provided with eyelets 12 for laces or lacing

cords 13, the sections being provided between the strips 11 with flexible portions 14 of relatively thin material so as not to cause any discomfort or bulging of the corset when the strips 11 are drawn close together by the corset laces 13.

10 The sections 1 and 2 are also connected at the back by a corset lace or lacing cord 15 arranged in eyelets 16 located at the rear edges of the sections 1 and 2 in the ordinary manner and the said sections are preferably provided at the back with bones or stiffeners 17 of any desired construction or material.

15 The corset is provided with shoulder straps 18 attached to the sections adjacent to the rear edges thereof and adapted to be carried over the shoulders of the wearer and pinned to the front of the corset, or otherwise secured to the same.

20 The section 1 of the corset is provided at the bottom of the front with a flexible inelastic strip 19 secured to the portions 4 and 5 and arranged to cover the lower edge of the lowermost strip 3 of elastic material.

25 The flexible portion at the side adjusting means is provided with a tapered approximately triangular insert 20 to produce the proper configuration of the corset at the lower portion.

What is claimed is:

A maternity corset comprising a pair of sections and one section being of a greater length than the other section to form a front portion, one side portion and a portion of the back of the corset, the second section 35 forming one side portion and a portion of the back, means adjustably connecting the sections together at their rear edges, a reinforcing fly formed on the front edge of the second section and adapted to underlie 40 the front edge of the first section, means detachably connecting the sections at their front edges, each section being divided in a pair of parts and elastically connected, lacing strings adjustably connecting the parts 45 of said sections, said front portion of the first section being constructed from relatively broad overlapping elastic strips that gradually increase in length from the lowermost strip, said strips having their upper 50 edges arranged in rear of the lower edges of the adjacent strip.

In testimony whereof I affix my signature in presence of two witnesses.

DR. CAROLINE E. ANDERSON.
